[57] **CLAIM**

The ornamental design for a bottle, as shown and described.

DESCRIPTION

FIG. 1 is an elevational view of a bottle showing my new design, the opposite side being substantially the same in appearance;

FIG. 2 is an elevational view looking from the right of FIG. 1, the opposite side being substantially the same in appearance;

FIG. 3 is a top plan view thereof; and

FIG. 4 is a vertical sectional view taken along lines A-B of FIGS. 1-3.
